UNITED STATES PATENT OFFICE

HENRY C. MEYERS, OF GRAND HAVEN, MICHIGAN, ASSIGNOR TO THE CHALLENGE MACHINERY COMPANY, OF GRAND HAVEN, MICHIGAN, A CORPORATION OF MICHIGAN

KNIFE GUARD

Application filed July 7, 1930. Serial No. 466,016.

This invention relates to a knife guard, being particularly concerned with a very practical and simple guard for the cutting edge of knives and which, among other of its places of use, may be used for guarding and protecting from injury the cutting edges of knives used with large or power operated paper cutters in printing establishments. The guard, however, is not restricted to this one named place of use.

It is necessary in a great many instances to ship the knives, which may be of considerable length, from the factory where they are produced to the manufacture of the paper cutting machines or, in cases where knives have to be replaced from either the knife or paper cutter manufacturer to the user of the machine. The edge of the knife is very sharp and needs to be guarded when thus shipped, both for the purpose of protecting the knife edge against injury, such as dulling, nicking or the like, and, further, to protect those who are called upon to handle the knife either during its shipment or before or after shipment.

The present invention is concerned with a particularly simple, yet exceptionally practical guard for knives which may be made in different lengths for different lengths of knives, and which may be instantly applied over the cutting edge of the knife serving to cover the same so that it will injure no one, and at the same time hold the cutting edge of the knife away from the guard whereby it will not be injured by the guard, while the guard itself protects the cutting edge from injury from outside sources.

An understanding of the invention for the attainment of the ends stated may be had from the following description taken in connection with the accompanying drawings, in which,

Fig. 1 is a plan of the blank of sheet metal from which the guard is made.

Fig. 2 is a perspective view illustrating the guard after shaping and forming from the blank, and

Fig. 3 is a vertical section through the guard showing a knife with its cutting edge

portion held within and protected by the guard.

Like reference characters refer to like parts in the different figures of the drawings.

The knife guard of the invention is to be made from a single sheet of metal 1, of rectangular form, which at its corners has outwardly extending tongues 2 and 3, preferably, as shown.

In forming the guard the blank of sheet metal described is bent longitudinally on one line, indicated in dotted lines at 4, and is formed into a loop substantially along the dotted line indicated at 5, thereby providing a guard having a vertical side, 6 which may be termed the front side, a shorter vertical rear side 7 spaced therefrom, an integral connecting section 8 extending downwardly toward the lower edge of the longer front side 6, the lower edges of the side 6 and the section 8 being integrally connected by the loop bend 9. In order to form the loop the lower portion of the front side 6 is bent outwardly, as indicated at 9a, for a short distance and the metal is then curved substantially in the arc of a circle until it joins with the lower edge of the section 8 described.

It will be evident that the section 8 is bent and formed in a curve from its upper to its lower portion concaved on its outer side and of convex form at its inner side. The tongues 2 and 3, which after the guard is formed into shape will extend from the ends and at the upper edge portions of the rear and front sides 7 and 6 respectively, are bent inwardly at right angles to overlap each other whereupon they may be permanently secured together in any suitable manner, as by spot welding, riveting or the like.

The guard as thus formed is to be applied over the cutting edge portion of the knife which is indicated fragmentarily and in section at 10 in Fig. 3. The knife has parallel vertical sides and has a downwardly inclined bevel 11 near its lower portion extending from the shorter vertical side to the longer vertical side thereby making the cutting edge 12 of the knife where the bevel 11 joins with the longer vertical side of the knife.

The longer vertical side of the knife bears

against the inner side of the longer vertical or front side 6 of the guard, the shorter side of the knife correspondingly bears against the inner side of the shorter rear side of the 5 guard and the bevel at 11 comes against the concave inner side of the section 8, with the cutting edge of the knife coming into the space enclosed by the loop 9.

By reason of the bearing of the bevel at 10 11 on the curved section 8 the cutting edge 12 of the knife is held away from the metal where it is formed into the loop 9, and the edge of the knife cannot come in contact with the metal. The connecting together of the 15 tongues 2 and 3 prevents any widening or separation of the two sides 6 and 7 of the guard and furthermore eliminates any possibility of longitudinal movement of the guard on the knife so as to wholly or partly dis- 20 engage therefrom.

It is evident that the blanks of sheet metal from which the guards are made may be cut to the necessary and desired lengths for different lengths of knives and that said blanks 25 may be readily and quickly formed and shaped to provide the guards, while the tongues 2 and 3 as previously stated, hold the sides of the guard rigidly with respect to each other and insure that the guard will remain 30 on the knife in so far as any longitudinal movement thereof is concerned. This structure protects the knife edge completely from any possible injury and the guard protects 35 persons handling the knives from any injury from the cutting edge of the knife.

The invention is defined in the appended claims and is to be considered comprehensive of all forms of structure coming within their scope.

40 I claim:

1. A knife guard of sheet metal having a vertical front side, a vertical rear side spaced from and parallel to the front side, the two sides having their upper edges in substantially the same plane, and the rear side being of less width than the front side, and a connecting section of sheet metal from the lower edge of said rear side to the lower part of 45 said front side and the lower part of the connection section being formed into a downwardly and slightly forwardly extending substantially U-shaped loop, and said connecting section being curved downwardly and forwardly to present a convex inner surface, 50 for the purposes specified.

2. A construction containing the elements in combination defined in claim 1, combined with ears integral with and extending from the ends of said front and rear sides of the 55 guard, said ears extending toward and overlapping and having permanent connection to each other.

3. In a knife having parallel sides and a bevel therebetween whereby a cutting edge 60 is formed, the combination of a guard of

sheet metal or the like formed from a single blank of flat metal with a relatively wide side, a narrower side spaced from and parallel to said wide side, and a connecting section between the lower edges of said sides, 70 said section contacting with the bevel at a point spaced from its cutting edge, then extending outwardly and around the cutting edge in spaced relationship whereby the cutting edge is maintained in perfect condition. 75

In testimony whereof I affix my signature.

HENRY C. MEYERS.
